ATTORNEY

UNITED STATES PATENT OFFICE.

HUGH EDWARD BROWN, OF PORTLAND, OREGON, ASSIGNOR OF ONE-HALF TO EDWARD BOYCE, OF PORTLAND, OREGON.

OIL-BURNER.

1,223,337.

Specification of Letters Patent. Patented Apr. 17, 1917.

Application filed August 4, 1916. Serial No. 113,183.

To all whom it may concern:

Be it known that I, HUGH EDWARD BROWN, a citizen of the United States, and a resident of the city of Portland, county of 5 Multnomah, State of Oregon, have invented a certain new and useful Improvement in Oil-Burners, of which the following is a specification.

This invention relates to the general type 10 of oil burners in which steam is employed to atomize the oil and place it in a state for ready ignition.

The object of my invention is to provide a simple and efficient burner in which the 15 steam is utilized to pre-heat the oil to the temperature of the steam before mixing therewith; also, by so pre-heating, to raise the temperature of the oil approximately to its own flash point. The oil, being given a 20 high degree of fluidity, the required pressure of the steam used for atomizing the oil is considerably lessened. The immediate pre-heating of the oil, furthermore, gives it a partial vaporization, and incidentally im- 25 parts a velocity to the jet of oil more nearly equal to that of the steam-jet.

A further object of my invention is to cause a more thorough and intimate intermixture of the oil and steam vapors by caus- 30 ing the two atomized fluids to become thoroughly intermixed and then passing the same through an intensely heated mixing chamber provided in the burner, this chamber being projected into the furnace and thus heated by the latter. A further object 35 of my invention is to so arrange the parts of my burner that it may be readily taken apart for cleaning.

The above specified and other incidental 40 features of my invention are hereinafter fully described, reference being had to the accompanying drawings, in which:

Figure 1 is a longitudinal, sectional plan view of my improved oil burner, taken on line A—A of Fig. 3.

Fig. 2 is a larger scale but similar sectional plan view of the spray nozzle of my burner as it appears in Fig. 1; and

Fig. 3 is a front end elevation of the 50 nozzle.

The body *a* of the oil burner constitutes a pre-heating chamber and is provided with a steam inlet pipe *b*. An oil pipe *c* is pro- 55 vided with a coil *d*, held in the heating chamber by means of the neck *e*, on which

is connected a packing box *f*, bearing a packing *f'* which prevents the escape of steam. The atomizing nozzle *g* is threaded on the front end of the oil pipe. A reducer *h* is threaded over the mouth of the heating 60 chamber, and threaded on its reduced end is a coupling ring *i*, provided with a bushing *j*, against which rests the inner face of the flange *k* of the spray nozzle. A flange nipple *l* and the bushing *j* clamp the flange 65 of said atomizing nozzle and by so doing hold the latter rigidly in place, and at the same time keep the oil pipe coil *d* centered within the heating chamber. A pipe *m* of substantial length, constituting an internal 70 mixing chamber, is threaded securely in one end into the nipple *l*, and on its free end is threaded the burner-tip *n*, which is preferably provided with a slotted orifice *o*.

The atomizing nozzle *g* (shown in Figs. 2 75 and 3) is provided with oil orifices *o*, preferably arranged in a common plane and comprising an axial orifice and a diverging ori- 80 fice on either side thereof, the divergence being from the nozzle chamber toward the outer or front face of the nozzle. The flange *k* of the nozzle is provided with steam ori- 85 fices *p*, made convergent as they approach the front face of the nozzle, and are pref- erably confined to the lower half, as shown in Fig. 3, so as to leave a mixing space ad- 90 jacent the exterior of the atomizing nozzle, in said mixing chamber, into which the steam vapors are not projected but in which they and the atomized oil may twirl around, and in so doing effect a more thorough in- 95 termixture. With this arrangement the steam and oil jets are made to intersect, and by so doing effect a thorough atomizing of the oil and a preliminary intermixture of the atomized oil and the steam vapor.

The steam enters the heating chamber *a* through the inlet pipe *b* from the boiler under a pressure controllable by a valve *r*, and at a temperature sufficiently high (ap- 100 proximately 330° F.) to pre-heat the oil to the necessary degree. The oil circulates through a brass or copper coil *d*, which it enters under a pressure of approximately forty pounds and at ordinary atmospheric 105 temperature. The coil *d* is made of suffi- 110 cient length to enable the oil, in passing through, to become heated to the tempera- ture of the steam. The sprays of oil and steam emitted from the atomizing nozzle *g*

become a very intimate and intensely hot mixture in the internal mixing chamber *m*, as already mentioned, and when passed out through the slot *q* of the burner *n* the mixture is in readiness for instant ignition.

5 The length of the coil pipe and the relative size of the preheating and mixing chambers must be proportioned to the size of the burner.

10 I claim:

1. In a burner of the type described, the combination of an elongate tubular body for the steam, a stuffing box at the inlet end of said body, an oil pipe having a part coiled within said body and its inlet end extending through said stuffing box, an atomizing nozzle secured at the discharge end of said body, said oil pipe having its outlet end secured to said atomizing nozzle, the latter being made with a peripheral flange, said nozzle having orifices comprising an axial orifice and a diverging orifice on either side thereof, said flange being made with converging orifices, a mixing chamber of substantial length affixed over said atomizing nozzle and its said flange, and a burner tip at the discharge end of said mixing chamber.

2. In a burner of the type described, the combination of an elongate tubular body for the steam, a stuffing box at the inlet end of said body, an oil pipe having a part coiled within said body and its inlet end extending through said stuffing box, an atomizing nozzle removably secured at the discharge 30 end of said body, said oil pipe having its outlet end removably secured to said atomizing nozzle, the latter being made with a peripheral flange, said nozzle having orifices comprising an axial orifice and a diverging orifice on either side thereof, said flange being made with converging orifices, a mixing chamber of substantial length removably affixed over said atomizing nozzle and its said flange, and a burner tip at the discharge end of said mixing chamber.

3. In a burner of the type described, the combination of an elongate tubular body for the steam, a stuffing box at the inlet end of said body, an oil pipe having a part coiled within said body and its inlet end extending through said stuffing box, an atomizing nozzle secured at the discharge end of said body, said oil pipe having its outlet end secured to said atomizing nozzle, the latter being made with a peripheral flange, said nozzle having orifices arranged in a common plane and comprising an axial orifice and a diverging orifice on either side thereof, said flange being made with converging orifices, a mixing chamber of substantial length affixed over said atomizing nozzle and its said flange, and a burner tip at the discharge end of said mixing chamber.

65 4. In a burner of the type described, the

combination of an elongate tubular body for the steam, a stuffing box at the inlet end of said body, an oil pipe having a part coiled within said body and its inlet end extending through said stuffing box, an 70 atomizing nozzle secured at the discharge end of said body, said oil pipe having its outlet end secured to said atomizing nozzle, the latter being made with a peripheral flange, said nozzle having orifices arranged 75 in a common plane and comprising an axial orifice and a diverging orifice on either side thereof, said flange being made with converging orifices in its lower half and being without perforations in its upper half, a 80 mixing chamber of substantial length affixed over said atomizing nozzle and its said flange, and a burner tip at the discharge end of said mixing chamber.

5. In a burner of the character described, 85 the combination of an elongate tubular body for the steam, a stuffing box at the inlet end of said body, an oil pipe having a part coiled within said body, and its inlet end extending through said stuffing box, a reducer threaded on the outlet end of said body, a bushing threaded on the outlet end of said reducer, a flanged coupling ring threaded on said bushing, a nipple made with a companion flange engaging with said flange of the coupling ring, said bushing being made with a recess, an atomizer nozzle provided with a peripheral flange seated in said recess, said oil pipe having its outlet end secured to said atomizing nozzle, the latter having orifices comprising an axial orifice and a diverging orifice on either side thereof, said flange of said atomizing nozzle being provided with converging orifices, a tubular mixing chamber of substantial 95 length threaded in said nipple, and a burner tip affixed on the outlet end of said mixing chamber.

6. In a burner of the character described, 100 the combination of an elongate tubular body for the steam, a stuffing box at the inlet end of said body, an oil pipe having a part coiled within said body, and its inlet end extending through said stuffing box, a reducer threaded on the outlet end of said body, a 110 bushing threaded on the outlet end of said reducer, a flanged coupling ring threaded on said bushing, a nipple made with a companion flange engaging with said flange of the coupling ring, said bushing being made 115 with a recess, an atomizer nozzle provided with a peripheral flange seated in said recess, said oil pipe having its outlet end secured to said atomizing nozzle, the latter having orifices located in a common horizontal plane and comprising an axial orifice and a diverging orifice on either side thereof, said flange of said atomizing nozzle being provided with converging orifices, a 120 tubular mixing chamber of substantial length 125 affixed to said atomizing nozzle, and a burner tip at the discharge end of said mixing chamber.

65 7. In a burner of the type described, the

threaded in said nipple, and a burner tip affixed on the outlet end of said mixing chamber.

7. In a burner of the type described, the combination of an elongate tubular body for the steam, an oil pipe extending through said tubular body, an atomizing nozzle secured at the discharge end of said body, and said oil pipe having its outlet end secured 10 to said atomizing nozzle, the latter being made with a peripheral flange, said nozzle having orifices comprising an axial orifice and a diverging orifice on either side thereof, said flange being made with converging orifices, a mixing chamber of substantial 15 length affixed over said atomizing nozzle and its said flange, and a burner tip at the discharge end of said mixing chamber.

HUGH EDWARD BROWN.
